TEA BAG SQUEEZER

Llewellyn W. Nelson, 4 Haviland St., Boston 15, Mass.

Filed May 17, 1961, Ser. No. 65,207

Term of patent 14 years

(Cl. D44—29)

A tea bag is shown by dotted lines in FIGURES 1 and 2 for illustrative purposes only.

I claim:

The ornamental design for a tea bag squeezer, as shown and described.
